UNITED STATES PATENT OFFICE.

THOMAS R. WILSON, OF ALTA, WYOMING.

TRACE-CARRIER.

1,300,085.

Specification of Letters Patent.

Patented Apr. 8, 1919.

Application filed July 25, 1916, Serial No. 111,307. Renewed September 28, 1918. Serial No. 256,142.

To all whom it may concern:

Be it known that I, THOMAS R. WILSON, a citizen of the United States, residing at Alta, in the county of Lincoln and State of Wyoming, have invented new and useful Improvements in Trace-Carriers, of which the following is a specification.

This invention relates to trace carriers, and it has for its object to produce a device of this class which will be simple in construction, which will have provision for the attachment of the hip straps as well as for the back band of the harness and in which spring means will be provided for retaining the cockeyes securely in engagement with their respective supporting hooks without interfering with the assembling or disassembling of the cockeyes with said hooks.

With these and other ends in view which will readily appear as the nature of the invention is better understood, the same consists in the improved construction and novel arrangement and combination of parts which will be hereinafter fully described and particularly pointed out in the claims.

In the accompanying drawing has been illustrated a simple and preferred form of the invention, it being, however, understood that no limitation is necessarily made to the precise structural details therein exhibited, but that changes, alterations and modifications within the scope of the claims may be resorted to when desired.

In the drawing,—

Fig. 1 is a top plan view of a trace carrier constructed in accordance with the invention.

Fig. 2 is a bottom plan view of the same.

Fig. 3 is a side elevation.

Fig. 4 is an end view.

Fig. 5 is a vertical sectional view taken on the line 5—5 in Fig. 1.

Corresponding parts in the several figures are denoted by like characters of reference.

The base frame 15 of the improved carrier is of oblong or oval shape, and it is provided at the ends thereof with separate loops 16 for the attachment of the hip straps. The back band is connected with the main frame intermediate the cross bars 17 which define the loops 16.

Rising from the base frame and integrally connected therewith is a crown comprising four limbs 18 rising from the main frame and connected by radial arms 19 with the

cap piece 20. The limbs 18 at the two ends of the main frame are connected together by braces 21 defining the bottom loops 22 and top loops 23; the cap member 20 is provided with lugs or hooks 24 depending within the loops 23. The cross bar 17 at one end of the frame is provided with upstanding lugs 25; secured by a rivet 26 on the other cross bar 17 is one end of a flat arched spring 27, the other end of which is fitted loosely between the lugs 25. The intermediate arched portion of the spring 27 abuts on the lower extremities of the hooks 24.

The manner of using the improved trace carrier will be readily understood. When the cockeyes are inserted through the loops 23 a downward pressure will depress or deflect the arched portion of the spring 27, permitting the cockeyes to be engaged with the hooks 24. The spring, by instantly resuming its initial position, will prevent accidental disengagement of the cockeyes from the hooks, and the trace will thus remain supported. To release the traces a downward pressure of the cockeyes against the spring 27 is all that is needed to enable the cockeyes to be released from the supporting hooks 24.

Having thus described the invention, what is claimed as new, is:

1. In a trace carrier, a base frame having terminal loops, cross bars defining the same, lugs rising from one of said cross bars, an arched spring secured on the other cross bar and terminally guided between the lugs, and a crown rising from the main frame and including a cap member having down-turned hooks terminally engaging the arched portion of the spring.

2. In a trace carrier, a base frame having terminal loops, cross bars defining the same, lugs rising from one of said cross bars, an arched spring secured on the other cross bar and terminally guided between the lugs, and a crown rising from the main frame and including a cap member having down-turned hooks terminally engaging the arched portion of the spring, said crown including limbs, radial arms connecting the limbs with the cap member, and brace members connecting the limbs adjacent to the ends of the frame.

In testimony whereof I affix my signature.

THOMAS R. WILSON.
